UNITED STATES PATENT OFFICE.

JESSUP SALISBURY, OF MOUNT CARMEL, CONNECTICUT, ASSIGNOR TO THE AMERICAN BUCKLE CO., OF NEW HAVEN, CONNECTICUT, A CORPORATION.

SLIDE BUCKLE.

Application filed July 16, 1928. Serial No. 292,970.

This invention relates to an improvement in slide-buckles and particularly to buckles especially adapted for use in overalls suspenders, the object being to provide a slide-buckle having superior capacity for holding the web against the various strains and stresses to which it is subjected in use.

A further object of this invention is to produce a structure having a maximum web-gripping ability and of such character that the eyes at the respective ends of its web-deflecting bar will not abrade the material of the garment to which the buckle is attached.

With these objects in view, my invention consists in a slide-buckle characterized by having its web-deflecting or cross-bar flattened to a substantial degree, wholly or in part, between the eyes at its respective opposite ends in a plane perpendicular to the axes thereof and transverse to the plane of the buckle-structure.

My invention further consists in a slide-buckle characterized as above and having certain other details of construction and arrangement of parts as will be hereinafter described and particularly recited in the claims.

In the accompanying drawings:

Fig. 1 is a face view of a buckle embodying my invention;

Fig. 2 is an under edge view thereof;

Fig. 3 is a sectional view thereof on the line 3—3 of Fig. 1;

Fig. 4 is a similar view on the line 4—4 of Fig. 1;

Fig. 5 is a view corresponding to Fig. 4 but showing a deflecting-bar of undulating form;

Fig. 6 is a face view of a slide-buckle provided with a deflecting-bar made of square wire; and

Fig. 7 is a sectional view on the line 7—7 of Fig. 6.

In the embodiment of my invention herein shown, I employ a frame formed from a single piece of wire bent into rectangular form to provide a top-bar 10, a parallel bottom-bar 11 and complementary parallel side-bars 12 and 13. Preferably, the ends of the wire meet midway the length of the bottom-bar 11 and are electrically welded together as at 14. The top-bar 10 and the bottom-bar 11 are each flattened on opposite sides of their centers as at 15 and 16, which flattened

portions assist in a large degree in holding the webbing and further provide a convenient surface upon which decorations, trademarks, etc., may be impressed.

Coming now to the novel feature of my invention, I employ a web-deflecting or cross-bar 17 preferably formed of round wire and having its opposite ends bent to form eyes 18 and 19 respectively encircling the side-bars 12 and 13 of the buckle-frame. The respective opposite sides of the major portion of the said bar 17 lying between the eyes 18 and 19, are flattened to a substantial degree as at 20 and 21 forming flat parallel surfaces located in planes perpendicular to the axes of the said eyes and hence in planes transverse to the plane of the buckle-frame.

The flattening of the bar 17 as above described results in widening the central portion thereof to form a web-deflecting reach 22 which overhangs to a considerable degree the top and bottom bars 10 and 11 of the frame, as clearly shown in Fig. 3, so that when a piece of webbing is threaded through the buckle, it will receive the maximum amount of deflection and as a result will be very firmly gripped. Furthermore, the flattening of the bar as described, not only provides a deflecting-reach of superior gripping capacity due to its substantially polygonal form in cross-section, but also greatly stiffens it and increases its ability to resist strains crosswise to the plane of the buckle-frame, which is the direction in which the major strains occur.

Preferably and as shown in Figs. 1 to 5 inclusive, the web-deflecting bar is formed from a piece of round wire so that when the same is flattened between its end-eyes, the latter will be of such rounded form as to avoid the chafing of the garment to which the buckle is attached.

If desired and as shown in Fig. 5, the deflecting and gripping capacity of the bar 17 may be further increased by imparting to it an undulating form.

In Fig. 6 I have shown the bar 17 formed from a piece of wire having initially rectangular form in cross-section. A web-deflecting bar of this form has the advantage of providing a well defined edge for co-action with the webbing, but as above noted I prefer to employ the round wire for the purpose, since it provides smooth rounded loops,

which are exposed beyond the side edges of the webbing, so that the abrasion of the garment is avoided.

I claim:

- 5 1. A slide-buckle comprising a frame; and a deflecting-bar formed of a single piece of wire folded at its respective opposite ends to form eyes adapted to encircle oppositely-located bars of the said frame and flattened to a substantial degree between the said eyes in a plane perpendicular to the axes thereof and in a plane transverse to the plane of the said frame.
- 10 2. A slide-buckle comprising a substantially-rectangular frame having parallel upper and lower bars and parallel side-bars; and a deflecting-bar formed of a single piece of wire folded at its respective opposite ends to form eyes encircling the respective side-bars of the said frame and flattened to a substantial degree between the said eyes in a plane perpendicular to the axes thereof, the flattened portion of the said deflecting-bar extending transverse to the plane of the frame in position to act in conjunction with the upper and lower bars thereof to deflect and hold a piece of webbing.
- 15 3. A slide-buckle comprising a substantially-rectangular frame having parallel upper and lower bars and parallel side-bars; and a deflecting-bar formed of a single piece of wire folded at its respective opposite ends to form eyes encircling the respective side-bars of the said frame and continuously flattened to a substantial degree between the said eyes in a plane perpendicular to the axes thereof, the flattened portion of the said deflecting bar extending transverse to the plane of the frame in position to act in

conjunction with the upper and lower bars thereof to deflect and hold a piece of webbing.

4. A slide-buckle comprising a substantially-rectangular frame having parallel upper and lower bars and parallel side-bars; and a deflecting-bar formed of a single piece of round wire bent at its respective opposite ends to form eyes encircling the respective opposite side-bars of the frame and flattened to a substantial degree between the said eyes in a plane perpendicular to the axes thereof, the flattened portion of the said deflecting bar extending transverse to the plane of the frame in position to act in conjunction with the upper and lower bars thereof to deflect and hold a piece of webbing; whereby smooth rounded non-abrading exposed eyes are located at the opposite ends of a deflecting-bar of substantially-polygonal form in cross-section.

5. A slide-buckle comprising a substantially-rectangular frame having parallel upper and lower bars and parallel side-bars; and a deflecting-bar of undulating form in a plane transverse to the plane of the said frame and folded at its respective opposite ends to form eyes encircling the respective side-bars of the frame and flattened to a substantial degree between the said eyes in a plane perpendicular to the axes thereof, the flattened portion of the said deflecting bar extending transverse to the plane of the frame in position to act in conjunction with the upper and lower bars thereof to deflect and hold a piece of webbing.

In testimony whereof, I have signed this specification.

JESSUP SALISBURY.
